UNITED STATES PATENT OFFICE.

WILLIAM H. RICHTER, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA.

INTERRUPTER MECHANISM.

1,418,881.

Specification of Letters Patent. Patented June 6, 1922.

Application filed October 22, 1919. Serial No. 332,438.

To all whom it may concern:

Be it known that I, WILLIAM H. RICHTER, a citizen of the United States, residing in the city and county of Philadelphia, State of Pennsylvania, have invented new and useful Improvements in Interrupter Mechanism, of which the following is a specification.

My invention relates to structure for interrupting an electric circuit, and particularly for interrupting the primary of the ignition circuit of an internal combustion motor.

My invention resides in apparatus of the character referred to comprising a base or plate member of insulating material in which is embedded a condenser and suitable inserts serving as terminals and supports for the interrupter members, suitable connections being formed or embedded within the insulating base.

My invention resides in apparatus of the character hereinafter described and claimed.

For an illustration of some of the many forms my invention may take, reference is to be had to the accompanying drawing, in which:

Fig. 1 is a plan view of the base plate.

Fig. 2 is a side elevational view of the same.

Fig. 3 is a fragmentary sectional view taken on the line 3—3 of Fig. 1.

Fig. 4 is a fragmentary sectional view taken on the line 4—4, Fig. 1.

Fig. 5 is a fragmentary sectional view taken on the line 5—5, Fig. 1.

Fig. 6 is a vertical sectional view, partly in elevation, of assembled interrupter and distributor mechanism embodying my invention.

Fig. 7 is a plan view of the structure illustrated in Fig. 6, with the cap and distributor arm removed.

Fig. 8 is a side elevational view of a modified structure embodying my invention.

Referring to the drawings, the base plate, supporting member or base plate 1 is of insulating material, preferably of condensite, bakelite or other suitable moldable insulating material.

Completely enclosed within the member 1 is the condenser C, of any suitable type, for example, rolled tin foil and paper,

placed in the mold for the member 1 and 55 molded within the same as the member 1 is made, the condenser being thus compressed by insulating material which serves also mechanically to protect it and to protect it from moisture. 60

There are molded in the member 1 the metal terminal bushings 2 and 3, preferably exteriorly knurled or roughened and interiorly threaded, and preferably having the exposed flanges 4 and 5. Surrounding the flanges 4 and 5 are the upstanding molded ribs 6, circumferentially incomplete, for admitting through the gaps the conducting leads with their terminals. Obviously these ribs 6 may be omitted. 70

Molded within the base plate 1 is the post 7 rising above the upper face of the member 1 and enclosed in the integral lug 8. In its upper end the post 7 is interiorly screw threaded to receive the screw 9 which holds the metallic member 10 firmly against the flat upper surface of the lug 8. Upon the downwardly extending end 11 of the member 10 is secured the stationary interrupter contact 12, with which co-acts the movable interrupter contact 13 carried by the arm 14 having at its free end the cam engaging tip or shoe 15 and secured at its other end to the leaf spring 16, secured to the vertically extending arm 17 of the bracket member whose horizontal member 18 is secured by screw 19 threaded into the post or bushing 20 molded in the base 1 and flush at its upper end with the horizontal surface of the slightly raised molded portion 21, having molded therein two depressions 22, 22, in which engage the projections 23, 23 on the under side of the plate 18. 85

A conductor 24, molded within the base member 1, connects the terminal bushing 3 with the post 7 and with one terminal 25 of the condenser C. A conductor 26, molded within the base 1, connects the other terminal 27 of the condenser C with the post 20 and the latter with the terminal bushing 2. 95

Extending centrally through the base member 1 is the hole 28, upwardly through which extends, Figs. 6 and 7, the cam shaft 29. 100

The base plate 1 has integral therewith the lugs 30 having the counterbored holes 31 through which extend screws 32 engag- 105

ing metallic housing 33, enclosing governor structure G changing, as well understood in the art, with changes in speed the angular relation between the aforesaid cam shaft 29 and the engine driven timer shaft 34, which is journaled within the hub 35, which may be integral with the member 33.

The cam shaft 29 has formed thereon the cam 36, Fig. 7, which in the example illustrated is hexagonal, there being an apex for each cylinder of the motor with which the interrupter apparatus is employed. The aforementioned shoe 15 upon the arm 14 is pressed by the spring 16 against the cam, which in rotating, causes the movable interrupter contact 13 to separate from and re-engage the stationary interrupter contact 12.

For advancing or retarding the spark the interrupter mechanism supported upon the member 1 is rotated by rotating the arm 37 on the member 33 about the axis of the shaft 34.

Enclosing the interrupter mechanism is the cap 38; also preferably of molded insulating material; resting at its lower edge upon the rim 39 of the member 1, and held by any suitable clamping means, not shown. Within the cap are disposed the usual high tension distributor terminals 40, 40, one for each cylinder of the motor, and the central high tension terminal 41, connected to one terminal of the secondary of the ignition induction coil, and in electrical communication with the contact 42 carried by and rotating with the distributor arm 43, preferably of molded insulating material, having a socket within which is the tongue 44 engaging in the slot 45, Fig. 7, in the upper end of the cam shaft 29. At the outer end of the distributor arm 43 is the usual contact 46 in electrical communication through the contact 42 with the high tension contact 41.

When the apparatus is in operation, in a manner well understood in the art, with the interrupter mechanism described connected in series in the primary circuit of the induction coil, by connecting the terminals 4 and 5 with conductors (not shown) extending through an aperture (not shown) in the cap 38, the interrupter contact 13 engages with and separates from the stationary contact 12, thereby interrupting the primary circuit and producing high tension impulses in the secondary circuit, which impulses are distributed by the aforementioned distributor mechanism to the spark plugs of the respective cylinders of the motor. The condenser C, as usual, reduces the sparking at the interrupter contacts 12 and 13, and so increases the intensity of the secondary impulses, the condenser being connected, as well understood in the art, across the break between the interrupter contacts 12 and 13.

In the construction described, both the members supporting the interrupter contacts are secured upon an insulating base member which insulates them from each other; they are connected by conductors within the base member with the terminals of the condenser, which is also embedded in the base member; and the terminals of the interrupter mechanism are held by and molded in the base member and connected by conductors within the same with the interrupter contacts.

For oiling the structure within the housing 33, there may be molded through the member 1 a hole 47 surrounded by the upwardly extending rim 48.

In Fig. 8 is illustrated a simplified construction in which the governor mechanism of the structure shown in Fig. 6 is omitted.

In this case the cam shaft 29 is integral with the engine driven timer shaft.

In this case the member 1 with the interrupter mechanism thereon as above described provided with terminals, posts and condensers, etc., molded therein, is mounted upon any suitable metal or other support or base 49 having the hub structure 50 in which the timer or cam shaft 29 has a bearing.

What I claim is:

1. Interrupter structure comprising a rigid base member of molded insulating material, fixed and movable interrupter contact members secured thereon and insulated from each other thereby, a condenser molded within said base member, and connections molded in said base member extending from the terminals of said condenser to said contact members.

2. Interrupter structure comprising a rigid base member of molded insulating material, metallic inserts molded in said member, fixed and movable interrupter contact members secured to said inserts, a condenser molded in said base member, and connections molded in said base member extending from the terminals of said condenser to said inserts.

3. Interrupter structure comprising a rigid base member of molded insulating material, fixed and movable interrupter contact members secured thereon and insulated from each other thereby, terminal inserts molded in said member, a condenser molded in said base member, and a connection for each of said terminal inserts molded within said base member and connecting with a terminal of said condenser and one of said contact members.

4. Interrupter structure comprising a rigid base member of molded insulating material, metallic inserts molded in said member, fixed and movable interrupter contact members secured to said inserts, terminal inserts molded in said base member, a condenser molded in said base member, and a connection from each of said terminal inserts molded in said

base member and connecting with a terminal of said condenser and one of said first named inserts.

5. Interrupter structure comprising a rigid base plate of molded insulating material having an aperture extending therethrough from one face to the other, a cam shaft extending through said aperture, a metallic member providing a shaft bearing, said base 10 plate secured to said metallic member, movable interrupter contact structure secured upon said base plate and cooperating with said cam shaft, and a stationary interrupter contact structure secured upon said base 15 plate and insulated thereby from said movable contact structure.

6. Interrupter structure comprising a rigid base plate of molded insulating material having an aperture extending therethrough from 20 one face to the other, a cam shaft extending through said aperture, a metallic member providing a shaft bearing, said base plate secured to said metallic member, movable interrupter contact structure secured upon said 25 base plate and cooperating with said cam shaft, a stationary interrupter contact structure secured upon said base plate and insulated thereby from said movable contact structure, and a condenser molded in said 30 base plate and having its terminals connected, respectively, within said base plate to said interrupter contact structures.

7. Interrupter structure comprising a rigid base plate of molded insulating material having an aperture extending therethrough from 35 one face to the other, a cam shaft extending through said aperture, a metallic member providing a shaft bearing, said base plate secured to said metallic member, movable interrupter contact structure secured upon said 40 base plate and cooperating with said cam shaft, a stationary interrupter contact structure secured upon said base plate and insulated thereby from said movable contact 45 structure, a condenser molded in said base plate and having its terminals connected, respectively, within said base plate to said

interrupter contact structures, and terminal members molded in said base plate and connected within the same with said interrupter 50 contact structures.

8. Combined interrupter and distributor structure comprising a metallic member forming a shaft bearing, a rigid base plate of molded insulating material secured upon 55 said metallic member and having an aperture extending from one face to the other, a cam shaft extending through said aperture, movable interrupter contact structure secured upon said base plate and coacting with 60 said cam shaft, fixed interrupter contact structure secured upon said base plate and insulated thereby from said movable contact structure, and a distributing cap of insulating material engaging at its end with 65 said base plate.

9. Interrupter structure comprising a rigid base plate of molded insulating material having an aperture extending therethrough from 70 one face to the other, a cam shaft extending freely through said aperture, a metallic member secured to said base plate and providing a bearing for said shaft, and interrupter contacts supported upon said base plate 75 co-operating with said cam shaft.

10. Interrupter structure comprising a rigid base plate of molded insulating material having an aperture extending therethrough from one face to the other, a cam shaft extending freely through said aperture, a metallic member removably secured to said base plate providing a bearing for said cam shaft, a condenser molded in said base plate, interrupter contacts supported upon said base plate co-operating with said 85 cam shaft, and terminal members and connections from said terminal members to said condenser and interrupter contacts, said terminal members and connections molded in said base plate.

In testimony whereof I have hereunto affixed my signature this 20th day of October, 1919.

WILLIAM H. RICHTER.
